UNITED STATES PATENT OFFICE.

WILLIAM EMERSON MORRIS, OF MARIETTA, OHIO.

TIE.

1,356,460.

Specification of Letters Patent. Patented Oct. 19, 1920.

Application filed July 6, 1920. Serial No. 394,163.

To all whom it may concern:

Be it known that I, WILLIAM EMERSON MORRIS, a citizen of the United States, residing at Marietta, in the county of Washington and State of Ohio, have invented new and useful Improvements in Ties, of which the following is a specification.

The present invention has reference to a metallic tie for railway rails and to means associated with the tie for holding the rails thereon.

The primary object is the provision of a metallic tie in which the sides and ends incline downwardly from the top thereof, and the said top has means thereon, whereby angle clamps engage with the base flange of the rails and may be adjustably secured thereon and retained in proper engagement with the rails.

A still further object is the production of a hollow metal tie with means for clamping the rails thereon which will permit of the arrangement of the clamps at varying desired positions transversely of the tie, but which will prevent the movement of the said clamps longitudinally or in a direction away from the rails which they engage.

A still further object is the provision in a metallic railway tie of means for clamping the rails thereon, and wherein the tie is provided with slots disposed to one side and arranged parallel with the base of the rails, openings arranged outward and at the center of each of the slots, and restricted passages between the openings and said slots, angle clamps engaging the base flange of the rails having their body portions overlying the slots and designed to be engaged by securing means that are of a construction whereby the same must be first passed through the openings, then directed through the restricted passages into the slots, and when so arranged and engaged with the clamps will be prevented from again entering the passages even should the said clamps become loosened.

The foregoing, and other objects which will appear as the nature of the invention is better understood, may be accomplished by a construction, combination and operative arrangement of parts, such as is disclosed by the drawings.

In the drawings:

Figure 1 is a plan view showing two rails arranged on a tie and secured to the same in accordance with this invention.

Fig. 2 is a greatly enlarged sectional view approximately on the line 2—2 of Fig. 1.

Fig. 3 is a sectional view approximately on the line 3—3 of Fig. 1.

Fig. 4 is a bottom plan view of the tie, with the rails secured thereto.

Fig. 5 is a plan view of a portion of the tie, the rails and the securing means therefor being removed.

Fig. 6 is a perspective view of one of the rail engaging clamps.

Fig. 7 is a similar view of the bolt member for engaging the clamp.

Fig. 8 is a longitudinal sectional view through the tie, illustrating a trough disposed beneath the slots for preventing the sinking of the bolts should the securing means therefor become disengaged therefrom.

The tie is indicated broadly by the numeral 1, the same comprising a hollow metal member constituting a flat top plate 2, outwardly inclined ends 3 and outwardly inclined sides 4.

On the top of the tie, adjacent to the ends thereof rest the rails 5. The top, in lines parallel with the longitudinal axis of the rails 5, and at points equidistant from the edges of the base flanges of the rails, is provided with transverse slots 6 which preferably have their end walls rounded. Outward of each of the slots 6, and approximately in a line with the center thereof, the top of the tie is provided with round openings 7. Between the openings 7 and the slots 6 are restricted passages 8.

The clamps for the rails comprise angle members, that is members that constitute rail contacting lips 9 and body portions 10 which are disposed below the lips. The body of each of the clamps has a bolt opening 11 therethrough.

The bolts which engage the clamps each include a head 12 which is of a size to freely pass through the openings 7. From the head extends a substantially rectangular shank 13. This shank is of a greater thickness than the width of the passages 8, but is of a size to be snugly received in and to contact with the opposed walls of the slots 6. The shanks 13 are of a length slightly less than the thickness of the top of the tie. From the shanks 13 are centrally extending reduced threaded portions 14 that are of a size to freely pass through the passages 8.

Thus, in arranging the bolts to engage

the clamps, it is necessary that the heads 13 as well as the squared portions 14 of the shanks thereof be passed through the openings 7 so that the reduced threaded extensions 14 may be brought in a line with the 5 passages 8, so that the bolts may be moved within the slots 6. The bolts are then elevated so that the squared portions 13 thereof are brought into the slots and contact, as 10 stated, with the opposed walls thereof. The bolts may be moved longitudinally to any desired point in the slots. The threaded portions 14 of the shanks are passed through the openings 11 in the body portions 10 of 15 the clamps, and thereafter nuts 15 are applied to the bolts. Suitable locking means may be provided for retaining the nuts locked on the bolts so that the clamps will be at all times firmly retained in rail 20 gaging position.

The heads 12 of the bolts preferably have their inner faces, on which the shanks are formed roughened or serrated, as at 16', and if desired, the under face of the top 2 of the 25 tie, opposite the walls of the slots therein may be likewise serrated, as indicated by the numeral 17. In addition to this, and as disclosed in Fig. 8 of the drawings, the under face of the tie may be provided with a 30 trough-like member 18 arranged to the sides of the slots 6, the said trough having an opening 20 that communicate with the passage 8. This trough effectively holds the bolts against sinking when the same are arranged on the tie, thus facilitating the 35 arrangement of the clamps on the bolts.

It is believed that the foregoing description, when taken in connection with the drawings will fully set forth the simplicity

of the construction, and the advantages 40 thereof to those skilled in the art to which such inventions relate. It is thought merely necessary to state that the rail engaging clamps may be variously positioned so that the same will effectively engage with the 45 rails, the said clamps, as previously stated, being positively held in rail engaging position. The shape of the tie is such that the roadbed will contact with the outwardly disposed sides and ends thereof, and the tie 50 will thus be held from sinking or from movement in either a lateral or longitudinal direction.

Having thus described the invention, what I claim, is:— 55

A hollow tie designed to have rails rest thereon, said tie having slots disposed at the sides and parallel with the base of the rails, openings arranged outward from the center of each slot, a restricted passage between 60 each opening and each slot, a trough beneath each slot, angle clamps for engaging the base flanges of the rails, bolts for engaging said clamps each including a headed member having a squared shank portion and a reduced threaded portion extending from the 65 said squared portion, said bolts designed to pass through the said openings in the tie to permit of the shanks being passed through the restricted passage and thereafter elevated to bring the squared portions of the shanks in contacting engagement with the opposed walls of the slots, the threaded portions of the bolts designed to pass 70 through the clamps, nuts engaging there- 75 with, and contacting the clamps.

In testimony whereof I affix my signature.
WILLIAM EMERSON MORRIS.
